(57) CLAIM

The ornamental design for a “dry goods dispenser,” as shown and described.

DESCRIPTION

FIG. 1 is a perspective view of one embodiment of the dry goods dispenser of the present design;

FIG. 2 is a frontal view thereof;

FIG. 3 is a back view thereof;

FIG. 4 is a right side view thereof; the left side view being identical in mirror image thereto;

FIG. 5 is a top view thereof;

FIG. 6 is a bottom view thereof;

FIG. 7 is a perspective view of another embodiment of the dry goods dispenser of the present design;

FIG. 8 is a frontal view of thereof;

FIG. 9 is a back view thereof;

FIG. 10 is a right side view thereof; the left side view being identical in mirror image thereto;

FIG. 11 is a top view thereof; and,

FIG. 12 is a bottom view thereof.

Features shown in broken lines in the drawings are not part of the claim.
